SAFETY MARKER FOR BICYCLES

John M. Kiniry, 107 Maple Drive 32937, and Anthony Finazzo, 5A Venetian Way 32937, both of Brevard, Fla.

Filed Sept. 28, 1972, Ser. No. 293,666

Term of patent 14 years

Int. Cl. D29—02

U.S. Cl. D10—111

FIG. 1 is a front view of a safety marker for bicycles showing a new design;

FIG. 2 is a side view thereof.

The rear of the marker is plain.

The indicia is shown in broken lines for illustrative purposes only.

I claim:

The ornamental design for a safety marker for bicycles, as shown and described in the drawing.
